UNITED STATES PATENT OFFICE.

DAVID F. NISBET, OF CRAFTON, PENNSYLVANIA; ASSIGNOR TO MACKINTOSH HEMP-HILL & CO., OF PITTSBURGH, PENNSYLVANIA, A CORPORATION OF PENNSYLVANIA.

ROLLING-MILL.

1,047,133.

Specification of Letters Patent. Patented Dec. 10, 1912.

Application filed March 8, 1912. Serial No. 682,396.

To all whom it may concern:

Be it known that I, DAVID F. NISBET, residing at Crafton, in the county of Allegheny and State of Pennsylvania, a citizen 5 of the United States, have invented or discovered certain new and useful Improvements in Rolling-Mills, of which improvements the following is a specification.

It has heretofore been the practice to construct three high blooming and roughing mills, having grooved rolls with the latter at predetermined distances apart, no provision being made for varying the vertical dimensions of the passes. Hence the product of 15 such a mill is limited, and when a product for which the grooves of the rolls were not adapted to produce, is desired, a change of rolls is necessary.

The invention described herein relates to 20 a mill of the three high type having grooved rolls, its upper roll adjustable with reference to the lower rolls and the middle roll movable by suitable means between the upper and lower rolls.

25 The invention is hereinafter more fully described and claimed.

In the accompanying drawings forming a part of this specification, Figure 1 is a side elevation of my improved mill; Fig. 2 is an 30 end elevation of the same; Fig. 3 is a sectional elevation, the plane of section being indicated by the line III—III Fig. 2; Fig. 4 is an end elevation of a portion of the mill illustrating a modification of improvement; Figs. 5, 6 and 7 show elevations of rolls embodying modifications of my improved mill 35 the roll shifting and adjusting mechanism being omitted, and Figs. 8 and 9 are sectional and end elevations of three high 40 blooming mills now in general use.

In the practice of my invention the lower roll 1 has its journals supported by bearing blocks 2 arranged at the lower ends of the windows in the housings 3. The middle 45 roll 4 and the upper roll 5 have their journals mounted in boxes 6 and 7 respectively, said boxes being vertically movable in guides 8 on the sides of the windows in the housing. The middle roll is arranged to be easily 50 movable up and down as hereinbefore described, by any suitable means known in the art. The construction shown is suitable for the purpose and consists of fluid pressure cylinders 9 suitably supported, and having plungers 10, which are provided with

cross-heads 11, and to the cross-heads are secured rods 12 bearing at their upper ends against the journal boxes 6 of the middle roll. By varying the pressure in the cylinders the middle roll may be raised or 60 allowed to move down prior to the entrance of the piece in a pass. The journal boxes 7 of the upper roll are yieldingly held against the ends of the adjusting screws 13 by fluid pressure cylinders 14 mounted on the housings. The plungers 15 of the cylinders support a cross-head 16 to which rods 17 are connected, said rods extending down through the caps of the housing and having their lower ends connected to the journal boxes 7, 70 as clearly shown in Figs. 2 and 3. Sufficient pressure is maintained in the cylinders 14 to yieldingly hold the journal boxes against the adjusting screws 13, which pass through nuts 18 in the caps of the housing, and may 75 be rotated by any means known in the art.

In the construction shown beveled pinions 19 are mounted on the screws and so connected thereto by keys, that the screws may move longitudinally through the pinions, but are caused to rotate therewith. These pinions are rotated by a reversible motor 20 through suitable interposed gearing. While not limiting the invention in this respect it is preferred to positively drive 85 not only the upper and lower rolls, but also the middle roll, as the frictional contact of the middle roll with the upper or lower roll as hereinafter described, may not be sufficient to overcome the resistance encountered by 90 the middle roll when heavy reduction is being effected.

As shown in Fig. 1 the journals of the several rolls are connected by spindles 21 to the journals of the pinions 22 in such manner 95 as will permit the vertical movements of the upper and middle rolls.

As clearly shown in Fig. 3 the several rolls which are grooved in accordance with rules known in the art, may be so constructed and proportioned that the collars of the middle roll will bear upon the corresponding collars of the upper or lower rolls, so that at 100 each pass the middle roll is supported and reinforced.

The advantages of my improved mill are, that it has as great range of out-put as the two high reversing mill now in use and avoids the necessity of reversing, the rolls being always driven in the same direction. 110

The advantages as to range of output as compared with three high mills having fixed grooved rolls will be readily understood by an algebraic statement taking w as representing the width of a pass and h as representing the height of a pass. Then in the old construction of a blooming mill shown in Figs. 8 and 9 the product of each of the passes as regards cross sectional dimensions will be represented by $w \cdot h$, both the height and width being fixed. But the product of the passes of my improved mill will be represented by $w (x h)$, x representing the adjustment of the upper roll. In a mill having fixed rolls with the number of grooves shown in Fig. 8, only that number of different products can be obtained, while in my improved mill with the same number of grooves in the rolls, the number of different products is indefinitely increased.

In lieu of constructing the rolls so that the collars of the middle roll will bear upon the corresponding parts of the upper and lower rolls, the boxes of the several rolls may be so constructed that those of the middle roll will bear on those of the upper and lower roll when the middle roll is shifted up and down, as shown in Fig. 4.

In Figs. 5, 6 and 7 are shown certain modifications of rolls adapted for use in my improved mill, said rolls having the reducing passes formed by grooves in one roll and the plain ungrooved portion of the adjoining roll. It will be understood that shifting and adjusting mechanism similar to that shown in Figs. 1, 2 and 3 will be employed for operating the middle and upper rolls shown in Figs. 5, 6 and 7.

By the term pass as used herein is meant a construction whereby the metal is held as against material lateral flow during reduction. This may be effected by grooving all of the rolls as shown in Fig. 2, by grooving the outer rolls, the intermediate roll being plain, as shown in Fig. 5, by grooving the intermediate roll, the outer rolls being

plain as shown in Fig. 6, or by grooving one of the outer rolls and the middle roll, while the other outer roll preferably the upper roll is plain or ungrooved, as shown in Fig. 7.

While not limiting myself in this respect it is preferred when employing grooved and plain rolls to form the passes that the boxes of the middle roll should bear against those of the upper and lower roll, when the former is shifted, as shown in Figs. 4, 5, 6 and 7.

I claim herein as my invention:

1. In a rolling mill, the combination of a stand of housings, three rolls arranged in said housings said rolls being constructed to form passes adapted to limit the lateral flow of the metal between the middle and upper and lower rolls, means for adjusting one of the outer rolls relative to the other outer roll, and means for shifting the intermediate roll to and fro between the outer rolls.

2. In a rolling mill, the combination of a stand of housings, three grooved rolls arranged in said housings, and means for adjusting one of the outer rolls relative to the other outer roll, the intermediate roll being movable to and fro between the outer rolls.

3. In a rolling mill, the combination of a stand of housings, three grooved rolls arranged in said housings, means for adjusting one of the outer rolls relative to the other outer roll, the intermediate roll being movable to and fro between the other rolls and means for driving the outer rolls.

4. In a rolling mill, the combination of a stand of housings, three grooved rolls arranged in said housings, means for adjusting one of the outer rolls relative to the other outer roll, the intermediate roll being movable to and fro between the other rolls and means for driving the rolls.

In testimony whereof, I have hereunto set my hand.

DAVID F. NISBET
